AUTOMOBILE REARVIEW MIRROR OR SIMILAR ARTICLE

Sol H. Lapidus, Great Neck, N. Y., assignor to U. S. Metal Products Company, Inc., New York, N. Y., a corporation of New York

Application December 7, 1955, Serial No. 39,201

Term of patent 7 years

(Cl. D14—6)

Fig. 1 is a three-quartered front perspective view of an automobile rear view mirror showing my new design;

Fig. 2 is a three-quartered rear perspective view of said mirror; and

Fig. 3 is a side view of said mirror.

The dominant features of the invention reside in the portions shown in full lines.

I claim:

The ornamental design for an automobile rear view mirror or similar article, substantially as shown and described.
